Primary Examiner — Lauren D McVey(74) *Attorney, Agent, or Firm* — Rumit Ranjit Kanakia(57) **CLAIM**

I claim the ornamental design for an electric fence element, as shown and described.

DESCRIPTION

FIG. 1 is a Perspective view of an electric fence element, showing my new design;

FIG. 2 is a Front view of the electric fence element as shown in FIG. 1;

FIG. 3 is a Back view of the electric fence element as shown in FIG. 1;

FIG. 4 is a Right-side view of the electric fence element as shown in FIG. 1;

FIG. 5 is a Left-side view of the electric fence element as shown in FIG. 1;

FIG. 6 is a Top view of the electric fence element as shown in FIG. 1; and,

FIG. 7 is a Bottom view of the electric fence element as shown in FIG. 1.

The broken lines in the figures depict portions of the article which form no part of the claimed design.
